MACHINE FOR FORMING FLAT STRIPS
INTO ARTICLES

Harold G. Woodburn, Munhall, Pa.

Application November 21, 1944, Serial No. 564,526

1. Claim. (Cl. 153—17)

1

This invention relates to machines for forming flat strips, the object being to expedite the forming of large numbers of flat strips so each is partly folded on itself with end portions bent inwardly respecting the folding.

A specific example of the invention is provided by the accompanying drawings illustrating a machine for forming thermocouple clips, the various figures being as follows:

Figure 1 is a front view;

Figure 2 is a top view;

Figure 3 is a front view of the clip produced; and

Figure 4 is a side view of Figure 3.

More specifically, these drawings illustrate the completed thermocouple clip to illustrate an example of the type of article it is desired to produce from the flat strips. This thermocouple clip must be made from a flat strip of spring bronze to provide the necessary electrical conductivity with mechanical elasticity, the strip being centrally folded parallel on itself quite closely at 1 and then loosely folded to provide straight flaring portions 2 with the ends of these latter portions right angularly bending inwardly at 3 respecting the foldings. The closely folded portion 1 is provided with registered holes 4 to which an electrical conductor may be connected by means of a bolt and nut, and the end portions 3 are provided with holes 5 which may be registered by springing together, or more closely folding, the straight portions 2 to bring the holes 5 into register, one of the thermocouple leads then being passed through this hole so that when the force required to spring the portions 2 together is released the resiliency exerted by the portions 2 urges the end portions 3 apart so as to jam the thermocouple lead tightly in the holes 5. Two of these clips are required for each thermocouple and in a plant using a great number of thermocouples quite large numbers of these clips are required. Prior to the present invention they have been commonly formed individually by hand.

The machine illustrated by the drawings includes a flat metal mounting plate 6 of sufficient thickness to provide structural rigidity, this plate mounting a unitary die block 7 having a flat surface 8 contoured to flatly support the spring bronze strip S with the end portions, which are to be the end portions 3 of the clip, overhanging the flat surface 8 and free for bending. This unitary die block 7 provides another surface opposite the surface 8, this other surface having flat portions 9 against which the strip S may be flatly positioned and being featured by hav-

2

ing a flat-sided recess 10 contoured for flatly-supporting partial-reception of the central portion of the strip S. Swinging levers 11 are pivotally fixed at 12 to the plate 6 so as to swing around the ends of the flat surface 8 of the die block 7, these levers 11 mounting punches 13 for engaging the overhanging ends of strip S when it is flatly supported by the surface 8 and bending these ends downwardly to provide the portions 10 3 of the clip; Stop pins 14 are mounted by the plate 6 in such a fashion that when the two levers 11 are swung downwardly, which may be done manually with the two levers swinging simultaneously, the punches 13 bend the overhanging ends of the strip S sufficiently far so that, considering spring-back, the right angular end portions 3 are formed. Preferably the levers 11 are provided with springs 15 which bias the levers 11 so that the punches 13 are maintained 20 at inoperative positions excepting during operation of the levers 11.

This swinging action of the punches provides for maximum simplicity but it creates the problem of providing some sort of stop for engaging the 25 ends of the strips as they are placed on the surface 8 and positioning them centrally of this surface with uniform amounts of overhang beyond its ends. This problem is solved by providing a retractable stop 16 mounted for sliding movement 30 at right angles to the surface 8 by a guideway 17 carried by the plate 6 in such a fashion that when the stop 16 is slid to a position beyond the level of the surface 8 it can be engaged by the ends of the strips as they are successively positioned on this surface to provide a means for 35 positioning these strips centrally of this surface 8, and when slid oppositely away from the level of this surface 8 the stop is retracted so it is cleared by swinging of the punches 13 when the 40 levers 11 are operating. Furthermore, this action is automatically effected by providing a means for effecting retraction of the retractable stop 16 to a position providing this clearness for the punch 13 working at the end of the surface 45 8 where this stop 16 is, and with this means powered by movement of this swinging punch for simultaneous retraction upon swinging of this punch. This means takes the form of a link 18 that is pivoted to the lever 11 and to the stop 50 16 so that as the lever swings to punch operating position it powers this stop 16 so as to cause its simultaneous retraction.

As so far described, provision is made for quickly placing the spring bronze strip on the 55 surface 8, positioning it by the stop 16 so that the

strip is properly centralized on this flat surface of the die block 7 and then by simultaneously swinging the levers 11 against the resiliency of the springs 15 quickly bending the right angular portions 3. Preferably the ends of the strips have already been punched to form the holes 5 prior to this described operation.

After each of the strips S has the end portions 3 formed it is next placed on the surface 9 of the same unitary die block 7 and is centralized there, such positioning requiring a stop similar to the stop 16 and this stop being preferably provided by forming the stop 16 with an offset surface 16^a properly positioned beyond the end of the surface 9 when the stop 16 is in its operative position. This means that the stop 16^a retracts with the stop 16 automatically but this causes no inconvenience. The recess 10 has a flared mouth 10^a and a punch 19 is provided having a flat tongue 20 which enters the flat-sided recess 10 and effects folding centrally of the strip to provide the portion 1 of the clip desired, along with a flared flat-sided portion 21 which works against the flared surfaces 10^a of the recess 10 to bend the portions 2 with the appropriate angularity respecting each other. This punch 19 must work linearly and is guided for reciprocation at right angles to the surfaces 9 parallel the surfaces of the recess 10 by a guide 22 mounted on the plate 6, this punch 19 being powered by a lever 23 pivoted at 24 to the plate 6 and connecting with the punch 19 through a link 25.

The further operation is relatively obvious, the strips having the end portions 3 of the clips formed as previously described are next successively positioned on the surfaces 9 by the aid of the stop 16^a with the ends 3 pointing opposite the working direction of the punch 19, the lever 23 then being moved to force the punch 19 so its tongue 20 enters the recess 10, this forming the closely folded portion 1 of the clip, and so its surfaces 21 work the strip against the flared surfaces 10^a of the recess 10 so as to bend the portions 2 of the clip to their proper angularities. Thereafter the holes 4 are punched to assure accurate registration.

The advantages of the machine reside in its great simplicity and inexpensiveness, this being achieved by making the single unitary die block

7 perform the multiple operations required to produce the clips and by permitting the use of the simple swinging punches 13 in conjunction with the stop required to properly position the strips on the die block surface providing strip support during operation of these punches 13. The whole machine is very sturdy and permits the production of the many clips required around the average plant using thermocouples at a much greater rate than was ever achieved when these clips were made by hand, while at the same time producing the clips with more exact contours than was ever before possible.

To prevent undue buckling of the strip S while it is being worked on the surface 8 as described, transverse bars 26 are arranged closely over this surface near its ends and under which bars the strip may be slid when being placed on the surface 8.

20 I claim:

A machine for forming a flat strip so it is partly folded on itself with end portions bent inwardly respecting the folding, said machine including a unitary die block having a flat surface contoured to flatly support the strip with said end portions overhanging said flat surface and free for bending and another surface having a flat-sided recess contoured for flatly supporting partial reception of the central portion of the strip, in combination with punches arranged to bend said end portions simultaneously and another punch arranged to force the strip centrally into said recess, when the strip is successively positioned on said surfaces, whereby to provide for the multiple operations required by the use of a single unitary die block, at least one of the first named punches swinging around the end of said flat surface of said die so as to prevent the use of a fixed stop there for engaging the end of the strip and centering it on said flat surface, and a retractable stop being arranged there for so engaging said end and for retraction out of the way of said swinging punch, in combination with means for effecting said retraction and with said means 40 powered by movement of said swinging punch for simultaneous retraction upon swinging of said swinging punch.

HAROLD G. WOODBURN.
